Design No 685.—
G. Smith, H. Brown & Jas. A. Read
Assignors to J. S. White & A. Lawrence

Design or PARLOR

FIG. II.

COOK STOVE.

FIG. 2.

G SMITH, H BROWN, & J A READ, ASSIGNEES TO

ABBOTT & LAWRENCE

DESIGN for PARLOR COOK STOVE

FIG. 3.

Garrettson Smith, Henry Brown, and
Joseph A. Read, of Philadelphia Penna

Assignors to

J. S. Abbott and A. Lawrence, of same place.

Letters Patent No 685. Dated Janst 2nd 1855. Ante-dated

Decth 30th 1854.

The schedule referred to in these Letters Patent, and making part of the same.

To all whom it may concern:

Be it known, that we Garrettson Smith, Henry Brown, and Joseph A. Read, of Philadelphia, State of Pennsylvania, have invented or produced a new and original Design for Parlor Cook Stove.

And we do hereby declare that the following is a full, clear, and exact description of the same, reference being had to the annexed drawings forming part of this specification, in which

Figure 1. is a front elevation.

Figure 2. is a side elevation. — and

Figure 3. is a top view of the stove. —

Similar characters of reference denote the same parts of Stove, and design. — In the elevations, symmetrical designs have but one half their

details shown, and in the top view, but one quarter is given, as the remainder is but a repetition of the portion shown. —

The front plate A. bears in bas-relief on its lower portion an ornament composed of scrolls a. and foliage b. entwined, and having the configuration shown in figure 1. a portion of the foliage c. sweeping upward, and enclosing the feed doors B. as shown in the same figure. Above the feed doors is the inscription "Patented 1854" in raised capitals, and numerals. —

The feed doors B. are of open work, and are formed by the combination of the scrolls d. and foliage e. the arrangement and configuration being as shown in figure 1. —

Above the feed doors B. are the oven doors C. each bearing on its panel an ornament in bas-relief, made up of scrolls and foliage, having the arrangement and configuration shown in the above named figure. —

The side plate is ornamented in bas-relief by a figure F. composed of foliage f. scrolls g. and sweeps h. the arrangement and configuration being as set forth in the semi-figure, delineated in figure 2. —

The top plate P. has a rim embellished with scrolls i. & sweeps k. arranged, and configured as shown in the drawings. Above & within this rim, is an open work plate E. formed by the interlacing of scrolls m. sweeps n. and foliage p. between the edge of the said plate, and the center finger Q. which is made up of entwined foliage r. and bands s. the entire design of this top plate being as set forth in the drawings. —

The foot X. is ornamented with sweeping foliage t. and lozenge projection u. in bas-relief, and terminates in w how w. The design, arrangement, and configuration being as set forth in figure 1. —

What we claim as our invention, or production, and desire to secure by Letters Patent, is

The design, configuration, and arrangement of the ornaments in bas-relief, as herein described, and delineated in the annexed drawings, forming an ornamental design for a parlor book stove. — — — — — In testimony whereof we have hereunto signed our names before two subscribing witnesses.
